(57) **CLAIM**

The ornamental design for a display support, as shown and
described.

DESCRIPTION

FIG. 1 is a front perspective view of a display support
showing our new design;

FIG. 2 is a front elevation view thereof;

FIG. 3 is a left side elevation view thereof;

FIG. 4 is a top plan view thereof; and,

FIG. 5 is a bottom plan view thereof.

The right side view of the design is a mirror image of the left
side view of FIG. 3. The rear view is omitted and forms no
part of the claimed design. The dashed-dotted broken lines
shown in the figures depict the bounds of the claim. The
dashed broken lines depict portions of the display support.
The broken lines form no part of the claimed design. The
pairs of jagged break lines joined by braces which wrap
around the vertical beam and the horizontal beams of the
display support apparatus indicate that the appearance of any
portion of the beams between the break lines forms no part
of the claimed design. In the left side view of FIG. 3, the pair
of jagged break lines and accompanying brace that is located
on the visible horizontal beam in the remaining figures have
been omitted from view for the purpose of not obscuring
portions of the claim.

1 Claim, 4 Drawing Sheets
